UNITED STATES PATENT OFFICE

NEVIL MONROE HOPKINS, OF NEW YORK, N. Y., ASSIGNOR, BY MESNE ASSIGNMENTS,
TO GILMONT PRODUCTS CORPORATION.

MULTIPLE-COMPARTMENT COLLAPSIBLE TUBE.

Application filed October 16, 1923. Serial No. 668,829.

This invention relates to multiple compartment collapsible tubes adapted to contain reacting liquids, and has for its object to improvement the constructions heretofore proposed.

With these and other objects in view the invention consists in the novel parts and combinations of parts constituting the tube, and in the novel package constituting an article of manufacture, all as will be more fully hereinafter disclosed and particularly pointed out in the claims.

Referring to the accompanying drawings forming a part of this specification in which like numerals designate like parts in all the views:

Figure 1 is a sectional view of the upper portion of a double compartment tube and cap closure made in accordance with this invention;

Figure 2 is a plan view of a modified form of the inner tube removed from the outer tube;

Figure 3 is an elevational view of the upper portion of the modified inner tube shown in Figure 1;

Figure 4 is a plan view of the parts shown in Figure 1;

Figure 5 is a sectional view taken on the line 5—5 of Figure 1, looking in the direction of the arrows;

Figure 6 is a diagrammatic sectional view of the completed double compartment tube provided with two photographic developing solutions having different properties and compositions; and

Figure 7 is a still further modified form of the invention provided with a straight conical neck on the tube 2.

1 indicates an outer collapsible tube preferably made of the usual pliable metal alloy, 2 a similar inner collapsible tube, 3 a screw threaded neck on the tube 1, 4 a suitable neck on the tube 2 adapted to fit liquid tight the opening 5 with which the neck 3 is provided as best indicated in Figures 4 and 5. The neck 3 is provided with one or more capillary grooves 6 whose dimensions are too small to permit liquid to pass when the other end 7 of the tube 1 is closed and no pressure is exerted on said tube, but said dimensions are sufficiently large to permit liquid to freely pass through the exits 6 when pressure is exerted

on said tube 1 as by rolling up said end 7 or by otherwise compressing said tube. It is found in practice that if these exits 6 are of a V-shape and are say in depth between 1/64 and 1/32 of an inch, while they are say about 1/16 to 1/32 of an inch in width, they will prevent the liquid 8 in the outer tube from escaping except when pressure is applied. The neck 4 of the inner tube is preferably provided with the chamber 9 as shown, and with the capillary orifice 10, which like the exits 6, is of such dimensions as will prevent the liquid 11 contained by the inner tube from escaping, except when pressure is applied to said inner tube. It is found in practice that a diameter of about 1/32 of an inch for the exit 10 gives satisfactory results. The extreme end 13 of the neck 4 is or may be slightly extended beyond the plane or surface 14 of the neck 3 as best shown in Figure 1, or it may be in the same plane as said surface 14, as indicated in Fig. 7. When said extreme end does extend beyond said surface 14, it contacts with the resilient or cork material 15 in the cap 16 when the latter is in its closing position as will be readily understood.

17 represents any suitable linings or coatings for the tubes 1 and 2, to protect the metal from the action of the liquids 8 and 11. These linings or coatings may be varied, in composition, to suit the chemical natures of the liquids 8 and 11 but ordinarily paraffine will be found satisfactory.

From the foregoing it will be clear that one may place in the outer tube 1 a liquid 8 and in the inner tube 2 a liquid 11 which would react with said liquid 8 and store these two liquids without suffering the deteriorations which would result if they were stored in a mixed condition.

In other words, it is well known, for example, that one of the present developers for photographic dry plates consists of two powders of different chemical compositions. One of these powders is usually dissolved in a certain volume of water to form what I may call "solution A". The other powder is likewise usually dissolved in a certain volume of water to form what I may call "solution B." These two solutions A and B are next usually mixed in a receptacle in the proportions of 1 part of solution A to 2 parts of solution B, and to the

mixture is next added another volume of water or seven parts thereof to form the completed developer, which must be used when freshly mixed to avoid deterioration.

5 In other words, as every photographer knows, after one has developed his photographic plate by the procedure heretofore practiced, he has not only been subjected to a considerable annoyance in preparing his solutions A and B, and his final solution, but he must throw away and lose what is left over of his said final solution.

10 With the aid of this invention, on the other hand, these objections are avoided, for I make up solution A of the proper strength and store it in the outer tube 1, where it becomes liquid 8 and will keep indefinitely. I also make up solution B of the proper strength and store it in tube 2 where it becomes liquid 11 isolated 15 from liquid 8, where it likewise will keep indefinitely. The capillary exits 6 and 10 prevent these liquids 8 and 11 from accidentally leaving their light tight containers, when the cap 16 is removed, and said cap keeps them 20 hermetically sealed when the light tight package is stored or shipped.

25 On the other hand, when one wishes to develop a photographic plate, he has only to remove the cap 16 and to exert pressure on the outer tube which will also compress the inner tube, or to roll up the end 7 of the two tubes, whereupon the two solutions 8 and 11 will at once be available for use. In order to deliver from the double tube container the two 30 liquids 8 and 11 in the right proportions, I prefer to make the exit orifices 6 and 10 of the same capacity, and to so vary the strengths of the solutions as to cause said exits to deliver the desired proportions of the chemicals 35 contained in the tubes 1 and 2. But, of course, the same results may be otherwise obtained, as by varying and properly proportioning the capacities of the two tubes.

40 In the somewhat modified form of the invention shown in Figures 2 and 3, the exit orifices 20 corresponding to the orifices 6 instead of being located in the neck 3 are located in the neck 4, otherwise the construction is or may be the same as in Figures 1 and 6.

45 In the still further modified form of the invention shown in Figure 7, the neck 21 corresponding to the neck 4 instead of being curved, is made cone shaped as illustrated, its coacting orifices 22 are accordingly made 55 straight instead of curved, and its extreme end 13 terminates in or near the plane 14 of the neck 3 as shown.

50 It will now be clear that in all the forms of the invention I have provided a double compartment collapsible tube with capillary exits adapted to contain and isolate during shipment and storage, a wide range of liquids of different compositions or properties, and to keep them in a fresh condition ready for instant use in the form of a mixture. It will

also be clear that this new tube and its contents constitute a new article of manufacture capable of sale as such.

It is obvious that those skilled in the art may vary the details of construction as well 70 as the arrangement of parts without departing from the spirit of the invention, and therefore, I do not wish to be limited to the above disclosure except as may be required by the claims. 75

What is claimed is:—

1. A multiple compartment collapsible container closed at one end and provided at its other end with a capillary exit in communication with the interior of one compartment and being of dimensions too small to permit a liquid to pass when not under pressure but of a sufficient size to pass said liquid when pressure is applied thereto, said multiple compartment container having also an exit in communication with the interior of another compartment and being provided with a common closure for said exits. 80

2. A multiple compartment collapsible container consisting of a pair of concentrically disposed collapsible tubes having neck portions provided with one or more capillary exits in communication with one compartment but otherwise fitting liquid tight the one within the other, said neck portions being also provided with an exit in communication with another compartment, the neck portion of the inner tube extending beyond the plane of the neck portion of the outer tube; and said tubes provided with a common closure. 85

90 3. A multiple compartment collapsible container consisting of a pair of concentrically disposed collapsible tubes provided with a lining and having neck portions fitting liquid tight the one within the other when not under pressure and said neck portions also provided with capillary exits adapted to pass liquid when pressure is applied, the neck portion of the inner tube extending beyond the plane of the neck portion of the outer tube; 105 and said tubes provided with a common closure. 100

110 4. A multiple compartment collapsible container having inner and outer compartments and closed at one end, having a pair of inner and outer relatively disposed neck members, said outer neck member being provided with an outwardly tapering or converging opening extending longitudinally therethrough, and the inner neck member being formed with a smooth tapered outer surface formed to fit within said tapered opening of the outer neck member to provide a liquid tight joint between said neck members, one of said tapered surfaces having one or 115 more grooves formed longitudinally thereof and providing an exit orifice in communication with the outer compartment so small as to prevent passage of liquid except under 120 pressure, and the inner neck member also be- 125 130

ing provided with an exit orifice in communication with the inner compartment.

5. The herein described article of manufacture comprising a plurality of collapsible tubes disposed one within another so as to provide separate compartments for the reception and isolation of different liquids, said

article having adjacent capillary exits in communication with the respective compartments and being too small to permit liquid to pass except under pressure.

In testimony whereof I affix my signature.

NEVIL MONROE HOPKINS.
